UNITED STATES PATENT OFFICE.

HARRY H. GARDNER, OF ROCKWOOD, PENNSYLVANIA.

FEED-BAG.

1,008,899.

Specification of Letters Patent. Patented Nov. 14, 1911.

Application filed July 15, 1911. Serial No. 638,627.

To all whom it may concern:

Be it known that I, HARRY H. GARDNER, a citizen of the United States of America, residing at Rockwood, in the county of 5 Somerset and State of Pennsylvania, have invented certain new and useful Improvements in Feed-Bags, of which the following is a specification, reference being had therein to the accompanying drawing.

10 This invention relates to feed bags, and the primary object of my invention is to support a feed bag from the hames or collar of a harness independent of the head, whereby the head can freely move.

15 Another object of this invention is to furnish a feed bag with an adjustable frame that permits of the feed bag holding any desired quantity of feed.

20 A further object of the invention is to provide a feed bag that is thoroughly ventilated, easy to clean and maintain in a sanitary condition.

25 With the above and other objects in view, the invention resides in the novel construction, combination and arrangement of parts to be hereinafter specifically described and then claimed.

30 Reference will now be had to the drawing, wherein there are illustrated the preferred embodiments of the invention, but it is to be understood that the structural elements thereof are susceptible to such variations and modification as fall within the scope of the appended claim.

35 In the drawing:—Figure 1 is a perspective view of a feed bag in accordance with this invention, Fig. 2 is an enlarged plan of the circular frame of the bag, Fig. 3 is a perspective view of a portion of the same, 40 and Fig. 4 is a horizontal sectional view of a portion of a modified form of feed bag.

A feed bag in accordance with this invention comprises front and rear curved straps 1 and 2 having the ends thereof provided 45 with guides 3 and 3^a for the ends 4 of curved side straps 5. The ends 4 of the curved side straps 5 are bent outwardly, as at 6 whereby the straps composing the circular frame of the bag cannot become accidentally disengaged.

Arranged upon the straps 1, 2 and 5 is the casing 7 of a flexible receptacle 8, preferably made of three pieces of strong and durable canvas, the ends of the centralmost piece being gathered upon the straps 1 and 2, whereby the straps 5 can be easily adjusted to enlarge the mouth of the receptacle. The casing 7 has openings providing clearance for eyes 9, carried by the guides 3, and attached to said eyes are the ends 10 of straps 11 55 adapted to be connected to the hames or collar of the harness (not shown). The casing 7 has additional openings to provide clearance for the guides 3^a and connected to said guides by rivets 12 or other fastening means 60 are rigid or rearwardly extending arms 13 having hook-shaped ends 14. These arms are adapted to be attached to the rings or hooks of the hames of a horse collar (not shown). 65

In Fig. 4 of the drawing there is illustrated a modification of the invention, wherein the bag has a solid ring 15 surrounded by a casing 16 and this casing is secured to the ring in such a manner as to 70 hold the angular ends 17 of the arms 13^a in engagement therewith. The forward ends of the straps 11 can be held in a similar manner.

75 What I claim is:—
A feed bag comprising a front and rear straps, side straps having the ends thereof adjustably held by the ends of said front and rear straps, a flexible receptacle having a casing adapted to receive said straps with 80 the casing gathered upon said front and rear straps, flexible straps connected to the front strap of said bag, and rigid arms connected to the rear strap of said bag, said arms and said flexible straps being adapted 85 to be connected to the hames or collar of a harness. 90

In testimony whereof I affix my signature in the presence of two witnesses.

HARRY H. GARDNER.
